UNITED STATES PATENT OFFICE.

EDWARD S. STIMPSON, OF HOPEDALE, MASSACHUSETTS, ASSIGNOR TO DRAPER CORPORATION, OF HOPEDALE, MASSACHUSETTS, A CORPORATION OF MAINE.

WARP STOP MOTION FOR LOOMS.

1,409,427.

Specification of Letters Patent. Patented Mar. 14, 1922.

Application filed June 4, 1921. Serial No. 475,015.

To all whom it may concern:

Be it known that I, EDWARD S. STIMPSON, a citizen of the United States, residing at Hopedale, in the county of Worcester and 5 State of Massachusetts, have invented an Improvement in Warp Stop Motions for Looms, of which the following description, in connection with the accompanying drawings, is a specification, like characters on the 10 drawings representing like parts.

This invention relates to warp stop motions for looms, which effect loom stoppage when a warp thread becomes broken or too slack.

15 One of the objects of the present invention is to provide a mechanical warp stop motion which shall be simple in construction and effective in operation, and wherein the parts shall be so combined as to occupy 20 a minimum space in a direction fore and aft of the loom and at the same time not interfere with the desired size and position of the warp beam.

Other features of the invention relate to 25 a novel construction and combination of parts, all as will be hereinafter more fully described in connection with the accompanying drawings which show one good form of means for carrying the invention into practical effect.

In the drawings:

Figure 1 is a perspective view showing a part of the warp stop motion proper;

Fig. 2 is a vertical section fore and aft 35 of the loom, and through the warp stop motion proper;

Fig. 3 is a perspective view showing the warp stop motion supporting means, the drop wire guides, and associated parts;

40 Fig. 4 is a perspective view of the feeler carrier, showing it in its raised or inoperative position;

Fig. 5 is an enlarged sectional detail showing the brace for bracing the feelers;

45 Fig. 6 is an enlarged detail showing a brace for bracing the drop wire guides; and

Fig. 7 is a sectional side elevation showing one unit of the warp stop motion containing the present invention.

50 The loom frame has secured to the sides thereof supporting means for the main parts of the warp stop motion proper, such supporting means being preferably provided as brackets 1, one at each side of the 55 loom, on which are adjustably mounted

brackets 2 which directly support the drop wire guides. The two brackets 1 and 2 may be connected together by appropriate slot and bolt connections, as indicated in Fig. 3, whereby the relation of the warp stop 60 motion proper with other parts of the loom may be readily effected. In the present instance of the invention the bracket 1 is provided with a slot 3 and the bracket 2 with a slotted projection 4, the projection and slot 65 3 being connected together by a bolt 5.

The upstanding flange of the bracket 2 is provided with recesses or openings for receiving the ends of the drop wire guides which may be held in place by suitable caps. 70 In the present instance of the invention, the brackets 2 are provided with the lugs 6, and at each side of a lug 6 the bracket 2 is provided with a recess 7 in which the end portion of one of the drop wire guides 8 may 75 rest. One wall 9 of each recess 7 is inclined, as best shown in Fig. 2, to the end that when the drop wire guide 8 is placed in position in its receiving and positioning recess on the bracket 2, it will be directed into 80 proper relation with and against the upright wall of the lug 6. When the drop wire guides 8 have been placed in their receiving and positioning slots on the brackets 2, they may be held in position by caps 10 (Fig. 3) 85 secured to the top portions of the lugs 6 by bolts 11.

The drop wire guides serve to direct the movement of the drop wires and to retain them in associated relation, as well as to 90 support the drop wires against the action of the feeler, as will later appear, when a drop wire is released by a broken or unduly slack warp thread.

Where the warp stop motion is located 95 between the warp beam or rear of the loom and the heddles, it is important that it be of minimum dimension fore and aft of the loom in order that it may be properly located with respect to the heddles and not interfere with a desired size in the warp beam or the warp wound upon the beam.

The drop wires 12 have enlarged upper ends 13 which, when a drop wire is released by a broken or unduly slack warp thread, 105 moves into the path of the feeler, as will presently appear, and arrests the detecting movement of the feeler. The edge portion of the drop wires 12 whereon is located the enlargement 13, will hereinafter be desig- 110

nated as the face edge, and the other edge as 14, will be noted as the back of the feeler. Each drop wire is provided with an elongated slot 15 and the drop wires are arranged 5 in rows, with one of the drop wire guides 8 passed through the elongated slot of the drop wires in a row. The slotted type of drop wire is preferably employed in the 10 present instance of the invention, but other forms of drop wires having enlargements along the face edge may be advantageously employed.

Two rows of drop wires constitute a unit 15 of the stop motion, as indicated in Fig. 7, and any number of such units may be assembled in the formation of the entire warp 20 stop mechanism. Inasmuch as the warp stop motion should occupy as little space fore and aft of the loom as possible, two rows of drop wires constituting a unit are arranged 25 in close relation back to back, with the enlargements 13 at the upper face edge of the drop wires extending in opposite directions. The drop wires, as usual in warp stop mechanisms, are each provided with a warp engaging portion which in the present instance of the invention comprises an eye or opening 16 formed in each of the drop wires, through which pass one of the warp threads *a*.

30 The warp threads adjacent the drop wires rest upon suitable warp supports. As shown, such supports are formed by bars or rods 17 and 18 which extend transversely of the loom frame and are preferably supported at 35 each end by socket portions 19 formed on the supporting brackets 2. The warp supports 18, which are located between the backs 14 of the drop wires, should interfere as little as possible with the close back-to- 40 back relation of the drop wires, and to this end the warp supports 18 are preferably made smaller in cross sectional dimensions than the other warp supports 17, as indicated in Figs. 2 and 7. In some cases, especially 45 where the loom is wide, it may be desired to brace the drop wire guides so that they may withstand the side pressure of the feelers transmitted through one of the drop wires when it is released by a broken or unduly 50 slack warp thread. In Fig. 3, four braces 20 are shown, but any suitable number may be employed. Each of the braces 20 is secured to a rod or bar 21 extending transversely of the loom and preferably supported 55 by the bearings 22 formed in the side supporting brackets 2. The rod or bar 21 may be secured to the brackets by suitable clamps 23. The braces 20 are shown provided with hub portions 24 which slide 60 along the rod or bar 21 and may be clamped in adjusted position by means of the bolts 25. The upper edge portions of each of the braces 20 are formed to engage and brace the drop wire guides, and as shown, each of 65 the braces 20 has one or more lugs 26, ac-

cording to the number of units comprising the warp stop motion; and at each side of the lug 26 the brace 20 is recessed to receive the end of the drop wire guide, as indicated in Fig. 6, one wall 27 of each recess being 70 beveled or cut-away to guide or direct the drop wire guide into proper position relative to the brace.

Each row of each drop wire unit of the warp stop motion has associated therewith 75 a feeler which acts only upon the drop wires of one row. In order that the warp stop motion shall not interfere with the desired size of the warp beam, the feelers are supported for their detecting movement above 80 the plane of the warp threads, and inasmuch as the feeler detecting movement is one of reciprocation, the feelers are arranged above the warp threads in a horizontal plane passing through the drop wire guides, the effect 85 being that when a drop wire is released by a broken or unduly slack warp thread, as indicated in Figs. 2 and 7, the drop wire guide on which the drop wire is hung will brace the part of the drop wire which is engaged 90 by the associated feeler. This condition is well illustrated by Fig. 2, wherein the drop wire at the left is indicated as having been freed by a broken warp thread *a*. It is at times desirable to run the loom without stopping it due to a warp fault, and to this end the present invention provides a feeler carrier which supports the feelers in position 95 above the plane of the warp threads with permissive movement of the feelers into inoperative relation with the drop wires by movement of the feelers heightwise of the drop wires from operative position.

In the present instance of the invention, the feeler carrier comprises the side members 100 28 preferably one at each side of the loom, and between the side members extend the feelers 29. The end portions of the feelers 29 are held in sockets or openings in the side members 28 of the feeler carrier, and, as hereinbefore described with respect to the support of the end portions of the drop wire guides, the slots in the side members 28 are arranged with one inclined wall 30 which serves to position the feeler 105 accurately on the side members of the feeler carrier when the feelers are engaged with the sockets. A cap-piece or cover 31 may be secured to the side members 28 by bolts 32 and serve to hold the ends of the feelers in 110 place.

Each side member of the feeler carrier is provided with a hub portion 33, Fig. 4, through which extends the rod or bar 34 and the hub portions of the side members may be 115 secured in the fixed position relative to the bar 34 by set screws 35. From the construction described, and as shown in Fig. 4, the feeler carrier comprises a frame which is removable from associated relation with the 120

other parts of the warp stop motion, and such removal is facilitated by the fact that the feelers themselves are supported and given their detecting movement in a plane 5 above the warp threads, so that the warp threads and drop wires do not interfere with ready removal of the feeler carrier.

In the present instance of the invention, the brackets 2 at each side of the loom 10 frame are provided with supporting guides 36 which extend outwardly as illustrated in Figs. 1 and 3. The side members 28 of the feeler carrier are provided with foot 15 portions 37 which may rest upon one of the supporting guides 36 of the brackets outside or beyond the end portions of the drop wire guides 8. The feeler carrier is given a reciprocating movement which, when interrupted by a released drop wire, will effect 20 loom stoppage through a train of mechanism well understood. In the present instance the brackets 2 have mounted thereon for rocking movement, the rock-shaft 38 to which is secured the operating arm 39 actuated 25 from a suitable train of mechanism common to warp stop motions for effecting loom stoppage when one of the drop wires is released by a broken or unduly slack warp thread. Secured to and rising from 30 the rock-shaft 38 is the arm 40, the upper end portions of which is bifurcated or has an open bearing 41 in which may be received the projection from the feeler carrier. In 35 the present illustration the projections for engagement with the bifurcated or open end 41 are furnished by the side projecting portions of the bar or rod 34, which may rest upon the shoulders 42 adjustably secured to the arm 40 as indicated in Fig. 3. The 40 construction is such that while the feeler carrier supports the feelers in position above the warp threads, and the side members 28 of the feeler carrier are supported beyond the ends of the drop wire guides 8, so that 45 the feeler carrier may be readily moved from operative position by lifting it relative to the drop wires, it may also be disengaged from its operating train of mechanism, so that the loom may run without stopping 50 when the attendant has moved the feeler carrier from operative position.

It may be desirable at times to brace the feelers 29, especially where they are used in a wide loom, and to this end a feeler brace 55 43 is adjustably mounted upon the rod or bar 34 and secured in adjusted position by a set screw 44. The feeler brace 43 has hook portions 45, 46 and 47, which are adapted to engage with the feelers 29, and while 60 supporting them in a vertical direction, also act to support them against deflection when one of the feelers is held and stopped by a drop wire.

The arrangement of the drop wires in 65 close relation back-to-back and with the

feelers above the plane of the warp threads, affords a warp stop motion of minimum dimension in the direction fore and aft of the loom, and one that will not interfere with the desirable size of the warp beam or the 70 amount of warp to be wound on the beam. Since, also, the feelers are mounted above the warp threads, they may be readily moved from operative relation with the drop wires to suspend the stopping function of the 75 warp stop motion.

What is claimed is:

1. In a warp stop motion for looms, the combination of drop wires each having an enlargement at its upper face edge and arranged in two parallel rows back-to-back, a pair of feelers arranged one at each side of the two parallel rows of drop wires and above the plane of the warp threads, means for moving the two feelers in the same direction toward and from the parallel row of drop wires included between them, and means for stopping the loom when either feeler is arrested by a drop wire. 85

2. In a warp stop motion for looms, the combination of slotted drop wires each having an enlargement at its upper face edge and arranged as a unit in two close parallel rows back-to-back, a drop wire guide passing through the slotted drop wires of 95 each row above the plane of the warp threads, a feeler arranged at each side of the two parallel rows of drop wires above the plane of the warp threads, a feeler carrier to which the two feelers are secured, 100 means for operating the carrier to cause the feelers to be reciprocated toward and from the two rows of drop wires included between them and each feeler to act only on the drop wires of one row. 105

3. In a warp stop motion for looms, the combination of slotted drop wires each having an enlargement at its upper face edge and arranged as a unit in two close parallel rows back-to-back, a drop wire guide passing 110 through the slotted drop wires of each row above the plane of the warp threads, a feeler arranged at each side of the two parallel rows of drop wires above the plane of the warp threads and having a detecting movement in the horizontal plane passing through the drop wire guides, a feeler carrier to which the two feelers are secured, 115 means for operating the carrier to cause the feelers to be reciprocated toward and from the two rows of drop wires included between them and each feeler to act only on the drop wires of one row. 120

4. In a warp stop motion for looms, the combination of a series of drop wires arranged in rows and provided each with an elongated guiding slot, a guide passing through the slots of the drop wires of each row, brackets at each side of the loom frame having slots with an inclined wall for posi- 130

- tioning and supporting the ends of the drop wire guides, removable caps for holding the drop wire guides in the slots, feelers, a feeler carrier having side members for supporting the feelers above the plane of the warp threads and beyond the ends of the drop wire guides that the latter and the drop wires may be readily removed from the loom.
- 10 5. In a warp stop motion for looms, the combination of drop wires having guiding slots, a drop wire guide substantially rectangular in cross-section passing through the guiding slots of the drop wires, a support at each side of the loom for supporting the ends of the drop wire guide and having receiving and positioning recesses, one wall of which is inclined to cause the drop wire guide to be properly positioned on the support when the ends of the guide are placed in the recesses.
- 15 6. In a warp stop motion for looms, the combination of a series of drop wires arranged in a row, a feeler carrier having side members, a feeler supported with its largest cross-sectional dimension in a horizontal plane above the plane of the warp threads and extending between the side members of the feeler carrier, and means for supporting and operating the feeler carrier that it may be moved from operative position above the warp threads by lifting it heightwise of the drop wires.
- 20 7. In a warp stop motion for looms, the combination of a series of drop wires arranged in a row, a feeler carrier having side members, a feeler supported with its largest cross-sectional dimension in a horizontal plane above the plane of the warp threads and extending between the side members of the feeler carrier, a brace for the feeler between the side members having hooked

portions which engage the feeler, and means for supporting and operating the feeler carrier that it may be moved from operative 45 position above the warp threads by lifting it heightwise of the drop wires.

8. In a warp stop motion for looms, the combination of a supporting bracket at each side of the loom, drop wires, drop wire guides supported by said brackets, a feeler carrier having side members supported beyond the ends of the drop wire guides, feelers extending between the side members of the carriers, and a cap-piece for securing the 50 end portions of the feelers to the side members of the feeler carrier.

9. In a warp stop motion for looms, the combination of a feeler carrier having side members provided with feeler positioning 60 slots one wall of which is inclined, a feeler extending between the side members of the feeler carrier and having its ends in said slots, and caps for securing the ends of the feeler in the positioning slots.

10. In a warp stop motion for looms, the combination of drop wires each having an enlargement at its upper face edge and arranged in two units each comprising two parallel rows with the drop wires of such 70 rows arranged back-to in close relation, a feeler arranged at each side of the two rows of drop wires comprising a unit and above the plane of the warp threads, a single feeler carrier to which all the feelers are connected 75 and by which they are reciprocated in their detecting movements above the plane of the warp threads that each feeler may act only on the drop wires of one row, and means for stopping the loom when the detecting movement of a feeler is arrested by a drop wire.

In testimony whereof, I have signed my name to this specification.

EDWARD S. STIMPSON.
